AMPLIFIER LINEARIZED BY NEGATIVE FEEDBACK

Hermann Bendel, Berlin, Germany, assignor to Siemens & Halske, Aktiengesellschaft, Siemensstadt, near Berlin, Germany, a corporation of Germany

Application December 4, 1936, Serial No. 114,175
In Germany December 12, 1935

4 Claims. (Cl. 179—171)

It is a well-known fact that non-linear distortions of an amplifier circuit arrangement may be diminished by means of negative feedback or degeneration. These non-linear distortions are reduced so much more markedly, the greater such degeneration may be made, that is to say, the more marked the reduction of the gain or amplification which is accomplishable, in the presence of stable conditions, by degeneration. However, a limitation is soon imposed upon degeneration by undesired phase shifts occasioned by coupling means. And in the presence of certain frequencies, spurious couplings arise which will cause the amplifier to oscillate.

In the accompanying drawing, Fig. 1 illustrates in schematic form an amplifier stage incorporating a usual form of negative feedback; Fig. 2 illustrates a form of the invention wherein the shield is connected to the junction point of the output transformer and the feedback resistance; Figs. 1a and 2a are simplified diagrams of the arrangements shown in Figs. 1 and 2 respectively; and, Fig. 3 illustrates in diagrammatic form an embodiment of the invention in a condenser resistance coupling circuit.

An essential part so far as the phase shifts are concerned, is played, inter alia, by the capacitances set up between the coupling means and other parts of the amplifier arrangement. Fig. 1 shows an amplifier stage comprising negative feedback of the usual kind. The load impedance B is associated by way of a transformer with the plate circuit of the tube. The input circuit E is connected between the grid and the junction point of the primary winding of the output transformer and the feedback resistance R_k . The shield S of the transformer is grounded in the usual way. This circuit scheme allows only comparatively little degeneration. In one particular case of a two-stage amplifier cascade, natural (spontaneous) oscillations were found to arise upon a reduction of the amplification of only 0.5 neper.

Starting upon the idea that the smallness of permissible degeneration is ascribable only to the shift of phase caused by the capacity C, certain circuit means and methods are suggested in this invention whereby essential capacities between the coupling impedance and the parts of the feedback impedance turned away from the said impedance are presented.

An exemplified embodiment of this basic idea is shown in Fig. 2. The shield S is not grounded, but is united with the joint or junction point of the output transformer and the feedback resist-

ance R_k . Contradistinct from what is the case in the circuit scheme Fig. 1, this precludes the arising of capacitances between the plate impedance and the end of the feedback resistance turned away therefrom. In Fig. 1, the capacitances represented by C are effective between the coupling impedance and the grounded screen S. These capacitances necessarily are also provided between the end of the feedback impedance which is away from the coupling impedance for the reason that this end is connected through ground to the screen.

Figs. 1a and 2a illustrate the corresponding equivalent circuit diagrams which make the effect of the capacitances upon the phase shift clear. Fig. 1a shows immediately that between the inner resistance of the amplifier tube and the feedback resistance there is inserted a quadripole (four-pole network) which, as is well known, occasions a considerable phase shift between the potentials arising across the inner resistance of the tube and the feedback resistance. The said shift consists of the phase shifts of the various elements so that, even in the presence of slight shifts of the constituent elements, the sum total of the shift may amount to 2π . In the circuit scheme Fig. 2a, a two-pole system is interposed between the inner resistance of the E. M. F. and the feedback resistance for which, of course, the phase shift may not be over

$$\pm\frac{\pi}{2}$$

The resistance of this two-pole system as a general rule is low in contrast with the coupling resistance R_k and the inner resistance of the tube (particularly where screen-grid tubes are used); hence, even if the two-pole network were to undergo a maximum phase shift, the current in the coupling resistance and thus also the feedback voltage would alter but inessentially.

The idea underlying this invention, as will be understood, is not confined to the output transformers of the amplifier tubes, but may analogously be used also in connection with input transformers. If coil rather than transformer coupling is involved, naturally the same conditions arise as regards the shift of the phases, though it may here be combated by the identical ways and means.

However, the value of permissible degeneration or negative feedback may be raised not only for purely inductive coupling means, but also in the case of condenser resistance coupling. A case of this kind is shown in Fig. 3. The plate circuit of

the amplifier tube contains a series arrangement comprising the coupling resistance R_a and the feedback resistance R_k . Inasmuch as the capacitances between the plate resistance and the base (or casing), especially where ultra-high frequencies are amplified, play an essential part, it follows that basically the same phase shift should be anticipated as with a circuit organization according to Figs. 1 or 1a. In other words, the 5 same phase shifts should be expected in the arrangement shown in Fig. 3 as are found in the arrangement shown in Fig. 1 for the reason that in Fig. 3 also the capacitances between the coupling resistance R_a and the base plate, that is, 10 ground, become very important. To be sure, the grounded end of the feedback resistance R_k is in this case so connected to the base plate or ground that the capacitances between the casing and the coupling resistance also exist between the grounded end of the feedback resistance 15 and the coupling resistance. What must also be taken into consideration in this connection is that for extremely high frequencies the inductive components of the so-called ohm coupling resistances should and could not be disregarded. Hence, in such a case, according to this 20 invention, a shield S is provided between the plate resistance and the grounded end of the feedback resistance with a view to precluding 25 capacitive couplings, the said shield being connected with the joint or junction point of R_a and R_k .

If a so-called voltage feedback rather than a current feedback as shown in Fig. 2 is concerned 30 in which the feedback potential is taken off across the terminals of a resistance connected in series with the load resistance, there apply fundamentally the same considerations for the elimination of undesired phase angle shifts. In the case of 35 voltage regeneration, as known in the prior art, the feedback voltage is taken off a voltage divider connected in parallel to the load. Such a circuit scheme is obtained, if the load resistance B as in Fig. 3 is connected in parallel relation to the series arrangement $R_a + R_k$ rather than to R_a . In 40 this instance, the portion of the voltage divider which is above point A should be surrounded by a shield which must be associated with point A. To what particular point should in such an instance be united the shield possibly provided for 45 the load resistance connected in parallel relation to the voltage divider will depend upon the requirements of a given case.

In a transformer-coupled screen-grid amplifier 50 which had been designed for handling from 100 to 20,000 cps., it has been feasible by using the invention to raise the admissible degeneration from 0.5 to 4 neper.

What I claim is:

60 1. In an amplifier circuit, an electronic tube provided with an anode, a cathode and a grid electrode, an input circuit for said tube including a pair of input terminals one of said terminals being connected to the grid electrode, an output circuit for said tube comprising a connection between the cathode and ground and a connection between the anode and ground, said last named connection including a coupling coil and a feedback resistance in series whereby one 65 end of the feedback resistance is grounded, a

connection between the other of said input terminals and the ungrounded end of the feedback resistance, a utilizing circuit, means including a coil coupled to the first mentioned coil for coupling the utilizing circuit to the output circuit of 70 said tube, and a shielding means interposed between said two windings, said shielding means being connected to the ungrounded end of said feedback resistance.

2. In a negative feedback amplifier, an electronic tube provided with an anode, a cathode and a grid electrode, an output circuit for said tube comprising a connection between cathode and ground and a connection between the anode and ground, said last named connection including a plate impedance device and a feedback resistor in series whereby one end of the feedback resistor is grounded, an input circuit for said electronic tube including a pair of input terminals, one of said terminals being connected to the grid 10 electrode, the other of said input terminals being connected to the ungrounded end of the feedback resistance, a utilizing circuit connected effectively across the plate impedance and means for shielding the plate impedance, said shielding 15 means being connected to the ungrounded end of said feedback resistor.

3. A linear amplifier comprising, an electronic tube having an anode, a cathode and a grid electrode, an output circuit for said tube comprising a shielded plate impedance and a feedback resistor connected in series in the order named between the anode and cathode of the tube, a shield 20 for the plate impedance, an input circuit for said tube including a pair of input terminals, one of said terminals being connected to the grid electrode, means for connecting the other of said terminals to said shield and to a point which is intermediate the plate impedance and the feedback resistor, means for connecting the cathode 25 end of said resistor to ground, a utilizing circuit including a pair of input terminals, means including a coupling capacity for connecting one of the last named input terminals to the anode of the tube and means for connecting the other of 30 said last two named input terminals to said intermediate point of the output circuit.

4. In amplifying apparatus an electronic tube having an anode, a cathode and a grid electrode, an output circuit for said tube comprising an output impedance and a feedback resistor connected in series in the order named between the anode and cathode of the tube, means for grounding the cathode of the tube whereby the end of the feedback resistor remote from the output impedance is grounded, an input circuit for said tube including a pair of input terminals, one of said terminals being connected to the grid electrode of the tube, the other input terminal being connected to the ungrounded end of the feedback resistor, a utilizing circuit effectively connected across the output impedance and means for preventing coupling between the output impedance and the grounded end of the feedback resistance through any inherent capacity effects 45 therebetween comprising a shielding means for said output impedance, said shielding means being conductively connected to the ungrounded end of the feedback resistor.
